[57] CLAIM

The ornamental design for a sink, as shown and de-
scribed.

DESCRIPTION

FIG. 1 is a perspective view taken from the top, front
and right side of a sink showing my new design;

FIG. 2 is a top plan view thereof;

FIG. 3 is a cross-sectional view taken on line 3—3 of
FIG. 2; and,

FIG. 4 is a cross-sectional view taken on line 4—4 of
FIG. 2.

The fragmentary broken line representation of a coun-
tertop in FIG. 1 is for the purposes of illustration only
and forms no part of the claimed design.
